Starco Company, Inc., St. Louis, Mo., a corporation
of Missouri

Filed Mar. 29, 1967, Ser. No. 626,856
3 Claims. (Cl. 52—73)

ABSTRACT OF THE DISCLOSURE

A prefabricated building including congruent top and base frames formed from endwise abutting angles having outwardly presented vertical flanges and upwardly presented horizontal flanges. The top and base frames are connected at their corners by upstanding corner angles having side flanges which are riveted to the vertical flanges of the top and base frames in such a manner that the intersecting vertical flanges and the intersecting side flanges are located adjacent one another. Side walls extend upwardly from the base frame and window frames are located above the side walls. A floor rests on the horizontal flanges of the base frame and a ceiling rests on and is secured to the horizontal flanges of the top frame. A roof extends across and covers the ceiling and a sliding or swinging door is formed in at least one of the side walls.

Small prefabricated buildings of a more or less portable nature are used for numerous purposes including guard-houses at factory entrances, attendant booths for parking lots and garages, in-plant offices, toll and ticket booths, and dressing rooms. Inasmuch as these buildings are often exposed to the elements they have heretofore been constructed generally of steel or wood covered with siding and have been generously reinforced by a number of reinforcing members. Consequently, these buildings are not only expensive, but also are quite heavy and therefore difficult to transport and emplace.

The prefabricated buildings of the present invention, on the other hand, are formed from a minimum of structural members which are interconnected in such a manner that the building is light in weight, yet possesses the same rigidity as similar prefabricated buildings heretofore constructed. By the same token, they are relatively inexpensive in cost.

Among the several objects of the present invention may be noted the provision of a prefabricated building which is durable and rigid in construction, yet light in weight; the provision of a prefabricated building which is weather-proof and attractive in appearance; and the provision of a prefabricated building which is economical to manufacture. Other objects and features will be in part apparent and in part pointed out hereinafter.

The invention accordingly comprises the constructions hereinafter described, the scope of the invention being indicated in the following claims.

In the accompanying drawings, in which several of various possible embodiments of the invention are illustrated:

FIG. 1 is a perspective view of a prefabricated building constructed in accordance with and embodying the present invention;

FIG. 2 is a sectional view taken along line 2—2 of FIG. 1;

FIGS. 3, 4, and 5, are sectional views taken along lines 3—3, 4—4, and 5—5, respectively, of FIG. 2;

FIG. 6 is a perspective view of a modified prefabricated building constructed in accordance with and embodying the present invention; and

FIG. 7 is a sectional view of the modified ceiling structure forming part of the present invention.

2

Corresponding reference characters indicate corresponding parts throughout the several views of the drawings.

Referring now to the drawings, 2 designates a prefabricated portable building having a rectilinear base frame 4 including a pair of side angles 6, 8, each consisting of an outwardly presented vertical flange 10 and an integrally formed upwardly presented horizontal flange 12. Transversely connecting side angles 6, 8, at their ends are end angles 14, 16, having outwardly presented vertical flanges 18 and integral upwardly presented horizontal flanges 20. Horizontal flanges 12, 20, are mitered at their ends and fitted into edgewise abutment so that the ends of vertical flanges 10, 18, are juxtaposed. Frame 4 is held together for the purpose of facilitating assembly by means of four triangular corner plates 22 which are riveted to the undersides of horizontal flanges 12, 20, across the mitered joints formed at the ends thereof (FIG. 4). Plates 22, of course, also add rigidity to base frame 4.

Extending upwardly from the corners of rectilinear frame 4 are four upstanding corner posts or angles 24, 26, 28, 30, each integrally including a pair of flanges 32, 34, disposed at right angles to one another. The inwardly presented faces of flanges 32, 34, fit against and are riveted to the outwardly presented surfaces of outer vertical flanges 10, 18, so that the V-shaped junctures formed by flanges 10, 18, on one hand and flanges 32, 34, on the other, are adjacent. Accordingly, the endwise abutting vertical flanges 10, 18, are joined together, thereby rigidifying base frame 4. A small portion of each post 24, 26, 28, 30, projects downwardly beyond base frame 4 in the provision of a foot 31.

At their upper ends upstanding corner posts 24, 26, 28, 30, are connected by a top frame 36 including a pair of side angles 38, 40, having integrally formed outwardly presented vertical flanges 42 and upwardly presented horizontal flanges 44, the angles 38, 40, being transversely connected at their ends by end angles 46, 48, also having outwardly presented vertical flanges 50 and upwardly presented horizontal flanges 52 which align with horizontal flanges 44. Similarly, the ends of horizontal flanges 44, 52, are mitered and brought into edgewise abutment while the vertical flanges 42, 50, in close proximity to their abutting junctures are riveted to the upper end of flanges 32, 34, of posts 24, 26, 28, 30, in such a manner that the V-shaped junctures formed by flanges 32, 34, on one hand, and flanges 42, 50, on the other, are adjacent. Similarly, riveted across the mitered joints formed by the abutting ends of horizontal flanges 44, 52, prior to installation on corner posts 24, 26, 28, 30, are upper corner plates 54 (FIG. 5).

Resting on horizontal flanges 44, 52, of top frame 36 and bolted thereto is a ceiling 56 consisting of an insulating board 58 having an aluminum sheet 60 laminated to the underside thereof. Extending completely across ceiling 56 and screwed thereto is a roof 62 which projects outwardly beyond the end and side margins of frame 36 and is preferably formed from corrugated aluminum. Attached to roof 62 and extending around the peripheral margin thereof are facia panels 64, the lower margins of which turn inwardly where they merge into gutters 66 located beneath the peripheral margins of roof 62.

Resting on and bolted to horizontal flanges 12, 20, of base frame 4 is a floor 70 preferably formed from a plywood board 71 having aluminum sheeting 72 laminated to its underside and a suitable floor covering 74 applied to its upwardly presented surface. The peripheral edge of floor 70 is located inwardly from the peripheral edge of base frame 4 a sufficient distance for permitting a pair of side panels 76, 78, and an end panel 80 to fit between the peripheral edges of floor 70 and flanges

32, 34, of upstanding corner posts 24, 26, 28, 30. The bottom edges of panels 76, 78, 80, furthermore rest on horizontal flanges 12, 20, of side angles 6, 8, and end angle 16 of base frame 4, and in slightly upwardly spaced relation therefrom panels 76, 78, 80, are secured to the adjacent peripheral edges of floor 70 preferably by means of wood screws. Adjacent their vertical margin panels 76, 78, 80, are securely attached to flanges 32, 34, of corner posts 24, 26, 28, 30, preferably by means of bolts. Side panels 76, 78, and end panel 80 are all preferably formed from an insulating board 82 having aluminum sheeting 84 laminated to its outwardly presented surface and a suitable hardboard 86 such as plywood laminated to its inwardly presented surface. The exposed surface of hardboard 86 facing the interior of building 2 is attractively finished.

Disposed above panels 76, 78, 80, are window frames 88, 90, 92, respectively, each having an upper lip 94, a lower lip 95, and lateral lips 96. Lateral lips 96 are riveted tightly against the inwardly presented surfaces of flanges 32, 34, of corner posts 24, 26, 28, 30, while the upper lips 94 of frames 88, 90, 92, are riveted to the inwardly presented faces of the vertical flanges on angles 38, 40, 48, respectively. Lower lips 95 of frames 88, 90, 92, lap over the outwardly presented faces of panels 76, 78, 80, to which they are securely fastened by means of bolts. If desired corner posts 24, 26, 28, 30, can be extended upwardly substantially beyond window frames 88, 90, 92, and another set of upper side panels can be secured to posts 24, 26, 28, 30, window frames 88, 90, 92, and top frame 36 in the manner previously described. In such an instance the portions of such panels along their upper edges would be riveted to the inwardly presented surfaces of vertical flanges 42, 50, on angles 38, 40, 48, while portions thereof along their lower margins would be bolted to upper lips 94.

Interconnecting end angle 14 of base frame 4 and end angle 46 of top frame 36 intermediate corner posts 24, 26, is a vertical member 100 of T-shaped cross-section having integrally formed forward and side flanges, the latter of which faces corner post 24 and is cut away at its ends so that the forward flange can abut against the outwardly presented faces of vertical flanges 18, 42, to which it is riveted. Enclosing the area defined by member 100, corner post 26, and end angles 14, 46, is a front panel 106 which is similar in construction to panels 76, 78, 80, and is furthermore secured in place along its peripheral margin by means of bolts which pass through the forward flange of member 100 as well as through flanges 32 and 50 of corner post 26 and end angle 46, respectively. The bottom edge of panel 106 rests on horizontal flange 20 of end angle 14 and slightly upwardly therefrom is secured to the adjacent end edge of floor 70 by means of a plurality of spaced wood screws. If desired, a portion of panel 106 can be replaced by a window frame which would be secured in place in a manner similar to frames 88, 90, 92. Riveted to vertical member 100, post 24, and angle 14 is a conventional door frame 108 of the storm door variety and swingably connected thereto by means of hinges 116 is a conventional outwardly opening aluminum door 118 which is provided with a handle and key operated lock assembly 120 for engaging a keeper formed in door frame 108.

Referring now to FIG. 6, it is possible to provide a modified prefabricated building 130 which is very similar to building 2 and also includes a base frame 132, upstanding corner posts 134, a top frame 136, a ceiling 138, a roof 140, and a floor 142, all of which are similar in construction to their counterparts in building 2. Building 130 is further provided with end panels 144, 146, and window frames 148, 150, which are emplaced similar to side panels 76, 78, and frames 88, 90, of building 2.

The sides of building 130 are enclosed by patio-type sliding door assemblies 152, 154, which are conventional in construction and design. It is, therefore, sufficient for purposes of the present disclosure to merely note that each door assembly 152, 154, includes upper and lower tracks 156, 158, the former of which are united to the horizontal flanges of the side angles forming part of top frame 136, while the latter rest on and are riveted to the horizontal angles of the side angles forming part of base frame 132. Interconnecting each pair of tracks 156, 158, intermediate their ends is an upstanding door post 160 and enclosing the area between post 160 and end panel 146 are side panels 162 and window frames 164. Slidably mounted on tracks 156, 158, are doors 166 which move from an open position wherein they are disposed in front of side panels 162 to a closed position wherein they enclose the area beyond upstanding door posts 160. It should be noted that door assemblies 152, 154, can be purchased having sliding doors which move either on the outside or inside of side panels 162. By the same token, it is possible to purchase door assemblies 152, 154, each having two movable doors located on parallel tracks so that one door can move adjacent the other.

Referring to FIG. 7, it is possible to provide buildings 2 or 139 with a modified ceiling 170 including a plurality of transversely extending spaced parallel extruded beams 172 of I-shaped cross-sectional configuration and having opposed upper and lower flanges 172, 174, interconnected by a bight portion 176. Lower flanges 174 are riveted securely to horizontal flanges 44 of the end angles forming upper frames 36, 136, and slidably fitted within the opposed channels of beams 171 formed by flanges 172, 174, and bight portions 176 are ceiling boards 177, each preferably consisting of an upper plywood panel 178, an intermediate layer of filter material 180, and a lower layer of ceiling tile 182, all adhesively bonded together. Fitted across upper flanges 172 of beams 171 is roof 62 or 140. If desired, extruded beams having an inverted T-shaped cross-sectional configuration can be utilized in lieu of I-shaped beams 171 and in such an instance ceiling boards 177 would merely rest on the lower flange of the T-shaped beams. Ceiling 170 is ideally suited for in-plant offices in view of the sound deadening characteristics possessed by ceiling boards 177.

In view of the above, it will be seen that the several objects of the invention are achieved and other advantageous results attained.

As various changes could be made in the above constructions without departing from the scope of the invention, it is intended that all matter contained in the above description or shown in the accompanying drawings shall be interpreted as illustrative and not in a limiting sense.

What is claimed is:

1. A building comprising a base frame of polygonal shape fabricated from a plurality of bottom angles having horizontally and vertically presented flanges, the latter of which form the outer periphery of the base frame, the latter of which extend downwardly of the horizontal flanges, a top frame of substantially the same size and configuration as the base frame and fabricated from a plurality of top angles having horizontally and vertically presented flanges, the latter of which extend downwardly from the horizontal flanges and form the outer periphery of the top frame, upstanding angles interconnecting the top and base frames and having side flanges which are secured to and facewise abut against the vertical flanges of the top and bottom angles at the corners formed by intersections of the various top and bottom angles, the upstanding angles upwardly terminating substantially no higher than the horizontal flanges of the top angles, a ceiling resting upon and secured to the horizontal flanges of the top angles, and a floor resting upon and supported by the horizontal flanges of the base frame, side panels secured to and held in facewise abutment with the inwardly pre-

sented surfaces of the side flanges, the peripheral edge of the floor being located in inwardly spaced relation to the vertical flanges of the base frame at a distance sufficient to permit the side wall panels to fit between the peripheral edge of the floor and the side flanges, whereby the lower edges of the side wall panels rest upon the horizontal flanges of the base frame and form a rigid rectilinear structure.

2. A building according to claim 1 and further characterized by a roof resting upon and fastened to the ceiling and projecting laterally beyond the top angles.

3. A building according to claim 1 wherein the top and base frames are rectangular and the vertical flanges of the top and base angles endwise abut so as to form V-shaped corners; and wherein the side flanges of the up-standing angles abut against the outwardly presented surfaces of the top and bottom angles with the lines of intersection formed by the side flanges being located adjacent to the lines of intersection formed by the abutting vertical flanges of the base and top angles.

4. A building according to claim 3 wherein the various horizontal flanges of the top and base frames are mitered at their ends and are located in endwise abutment with one another.

5. A building according to claim 4 in which at least one of the sides is enclosed by a sliding door assembly comprising a track, a door slidably mounted on the track and a stationary side panel, the remaining sides being enclosed by stationary wall panels and window frames.

6. A building according to claim 4 and further characterized by triangular corner plates riveted to the horizontal angles and disposed across the mitered junctures thereof whereby to maintain the upper and lower frames rigid.

5

10

15

25

30

7. A building according to claim 1 and further characterized by window frames located above the side panels and having laterally projecting, upwardly projecting and downwardly projecting lips, the laterally projecting lips overlapping and being secured to the side flanges of the upstanding angles and the upwardly and downwardly projecting lips overlapping and being secured to the vertical flanges of the top angles and to the side panels, respectively.

8. A building according to claim 7 in which the ceiling comprises a plurality of spaced parallel beams each having a vertical portion interposed between pairs of co-planar laterally projecting flanges which rest upon the horizontal flanges of the top angles, and ceiling boards resting upon the laterally projecting flanges.
